UNITED STATES PATENT OFFICE

FREDERICK G. THWAITS, OF WAUWATOSA, WISCONSIN, ASSIGNOR TO THE HEIL CO., OF MILWAUKEE, WISCONSIN, A CORPORATION OF WISCONSIN

CLOSURE

Application filed February 25, 1931. Serial No. 518,048.

The present invention relates in general to improvements in the construction and operation of removable closures for openings in housings of various kinds.

5 A general object of the invention is to provide an improved detachable closure which is simple in construction and which is moreover highly efficient in operation.

Certain types of housings, such as tanks 10 used for the storage and transportation of milk or the like, must be provided with openings for permitting access to the interior thereof for cleaning and inspection purposes. It is necessary that such housings or tanks 15 be maintained in highly sanitary condition, and any closure devices employed for the purpose of permitting access to the interiors of these tanks, must facilitate the maintenance of such conditions while at the same 20 time permitting both convenient access through and tight sealing of the openings. In order to enable tight sealing of these openings, the closures are ordinarily applied within the housings, thus utilizing the liquid pressure 25 sure to assist in sealing and also protecting the closure plates by confining them within the contour of the housings.

It is a more specific object of the present 30 invention to provide a removable closure for housings, such as tanks, which may be readily removed or closed to provide a perfect seal.

Another specific object of the invention is 35 to provide closure structure which may be conveniently cleaned and maintained in sanitary condition.

Still another object of the invention is to provide closure mechanism which is extremely simple, compact and rigid in construction, 40 and which produces least undesirable obstruction both when the closure is open or closed.

A further specific object of the invention is 45 to provide a highly effective internal closure which may be manufactured and applied to a housing at minimum cost.

Another specific object of the invention is 50 to provide a removable closure structure which may be quickly and conveniently manipulated to either expose or close an opening with which it cooperates.

These and other objects and advantages of the invention will appear from the following detailed description.

A clear conception of an embodiment of the invention and of the mode of constructing and of manipulating devices built in accordance therewith, may be had by referring to the drawings accompanying and forming a part of this specification in which like reference characters designate the same or similar parts in the various views:

Fig. 1 is a central longitudinal section through a fragment of a tank and through the closure mechanism associated with an opening therein, the section being taken along the line 1-1 of Fig. 2, looking in the direction of the arrows, and the plate being shown in closed position;

Fig. 2 is an external plan view of the fragment of the tank and closure shown in Fig. 1;

Fig. 3 is a transverse central section through the tank fragment and closure of Figs. 1 and 2; and

Fig. 4 is a part sectional view similar to that of Fig. 1, showing the closure plate removed to open position.

While the improvement has been shown and described herein by way of illustration, as being specifically applied in a closure especially applicable to the openings of milk storage tanks, it is not contemplated to limit the scope of the invention. The improvement is obviously more generally applicable to closures for openings in housings of various types, and has added utility when applied to internal seatings adjoining the openings in such housings.

Referring generally to the drawings, the housing or tank 5 has one or more inspection openings 6 therein which are customarily designated as man-holes. Each of the openings 6 may be provided with a metallic liner having a plane seating 7 disposed within the tank 5 and surrounding the adjacent opening 6. A closure plate 8 which is pivotally supported at one end of a double suspension lever 9, is adapted to coact with an adjacent seating 7 as shown in Fig. 1, or may be swung open as shown in Fig. 4. A bridge beam or member 10 pivotally associated with the tank

5 is adapted to coact with the medial portion of the lever 9 through a removable pin 11 so as to force the corresponding plate 8 against its seating 7.

6 The tank 5 may be formed of double sheet metal with cork or other insulation interposed between the sheets, and the seating liners may be rigidly attached to the tank sheets by welding or otherwise. The closure plates 8 as well as the tank structure, are preferably formed of rust-resisting material which may be highly polished for sanitary reasons, and each of the plates 8 may be provided with a resilient seat 13 adapted to coact with the adjacent seating 7 to insure a perfect seal. While the opening 6 of the device shown in the drawings, is of elliptical shape, these inspection openings may be circular or of any other desired formation.

20 The closure plate 8 is pivotally attached to the laterally extending end portions 14 of the lever 9, by means of a removable pin 15, and the portions 14 may be rigidly connected by means of an integral cross-brace 16. The 25 opposite end of the supporting lever 9 is pivotally attached to a supporting bracket 17 secured to the exterior of the tank 5 at one side of the opening 6, by means of a removable pivot pin 18, and the adjacent end of the 30 bridge member 10 is likewise pivotally attached to the same bracket 17 by means of a pin 19. While the lever 9 and member 10 have been shown as being pivotally supported by means of independent pins 18, 19, it 35 may in some cases be desirable to dispense with one of these pivot pins and to utilize a single pivot for both of these elements. The bridge member 10 is adapted to span the opening 6 between the spaced side portions 40 of the lever 9, and is provided with a medial socket with which the pin 11 is adapted to coact as shown in Fig. 1. The swinging end of the member 10 is provided with a threaded bushing 20 with which a spindle 21 is adjustably associated. The outer end of the spindle 21 is provided with a hand wheel 22, and the opposite end thereof is formed for coaction with a socket 23 secured to the tank 5 adjacent to the side of the opening 6 opposite to the bracket 17.

When the elements of the closure structure are positioned as indicated in Figs. 1, 2 and 3, the bridge member 10 by virtue of its coaction with the cross pin 11, may be utilized 55 to force the seat 13 of the closure plate 8 into snug engagement with the seating 7, by merely manipulating the hand wheel 22 of the spindle 21. It will be apparent that any degree of sealing can readily be obtained by turning the hand wheel 22 to force the swinging end of the member 10 outwardly.

By releasing the spindle 21, the coacting elements may be loosened sufficiently to permit free withdrawal of the cross pin 11, 60 whereupon the beam member 10 may be

swung away from the inspection opening 6 as shown in Fig. 4, and the lever 9 may be swung inwardly through the opening 6 so as to position the plate 8 out of alignment with the opening 6 and remote from the seating 7. After the closure plate 8 has been thus swung into the tank 5, the interior of the tank is freely accessible through the opening 6, without obstruction.

70 In order to completely dismantle the structure for cleaning purposes, it is only necessary to remove the pivot pins 15, 18, 19, whereupon the plate 8 may be removed from the lever 9, and the lever 9 and member 10 may likewise be removed from the bracket 17. By virtue of the elliptical formation of the opening 6, the closure plate 8 may then be freely removed from within the tank 5, the opening 6 being of greater major diameter than the plate 8 is of minor diameter.

75 From the foregoing description, it will be apparent that the present invention provides a closure structure wherein the closure plate may be readily removed from the adjacent opening, or closed to provide a perfect seal. The structure may obviously be quickly and conveniently dismantled for cleaning purposes, thereby permitting maintenance of the desired sanitary conditions. While being highly efficient, the closure structure is extremely simple, compact and rigid in construction, and when the closure plate 8 is completely withdrawn from the opening 6, this opening is entirely devoid of obstructions except for the lever 9 which extends 80 therethrough. The location of the closure plate 8 within the tank 5, obviously protects this plate against damage, and produces minimum projections at the exterior of the tank. While the elements of the embodiment 85 of the invention specifically shown in the drawings, are especially adapted for horizontal swinging of the lever 9 and the member 10 while the pivot pins 15, 18, 19 are disposed vertically, the closure may obviously be disposed 90 in any desired manner.

95 It should be understood that it is not desired to limit the invention to the exact details of construction and to the precise mode of operation herein shown and described, for various modifications within the scope of the claims may occur to persons skilled in the art.

100 It is claimed and desired to secure by Letters Patent:

125 1. In combination, an element having an opening, a closure plate for said opening, a lever having one end pivotally associated with said element and having said plate supported from the opposite end thereof, and a member having one end pivotally associated with said element at one side of said opening and having its other end adjustably associated with said element at the opposite side 130

- of said opening, the medial portion of said member being cooperable with said lever.
2. In combination, an element having an opening, a closure plate for said opening, a lever having one end pivotally associated with said element and having a lateral extension at its opposite end pivotally connecting said opposite end with said plate, and a member having one end pivotally associated with said element at one side of said opening and having its other end adjustably associated with said element at the opposite side of said opening, the medial portion of said member being cooperable with said lever.
- 10 3. In combination, a tank having an opening and a seating surrounding said opening with the exterior of said tank and cooperable with said seating, a lever having one end pivotally associated with the exterior of said tank and having its opposite end directed laterally through said opening, said plate being pivotally supported by said opposite lever end, a bridge member pivotally associated with the exterior of said tank and cooperable with the medial portion of said lever, and means for moving said bridge member to force said plate against said seating.
- 20 4. In combination, a tank having an opening and a continuous seating extending into said tank and surrounding said opening, a closure plate having a resilient seat cooperable with said seating, a lever having one end pivotally associated with said closure plate and having its opposite end pivotally associated with said tank, a member bridging said opening and movable associated with said tank on opposite sides of said opening and cooperable with the medial portion of said lever, and means for moving said member to force said plate into closed position.
- 30 5. In combination, an element having an opening, a closure plate for said opening, a lever having one end pivotally associated with said element and having said plate supported from the opposite end thereof, a member pivotally associated with said element and cooperable with said lever to force said plate into closed position, and means for adjusting said member relative to said element.
- 40 6. In combination, an element having an opening, a closure plate for said opening coacting with one side of said element, a lever pivotally associated with said element and with said plate to swingably support the latter, a beam member movably associated with said element at spaced points on the opposite side of said opening and engaging said lever to force said plate into closed position, and means for moving said beam member relative to said element.
- 50 7. In combination, an element having an opening, a closure plate for said opening, a lever pivotally associated with said element and with said plate to support the latter, a beam member pivotally associated with said element adjacent an end of said lever, said beam member cooperating with the medial portion of said lever to force said plate into closed position, and means for adjusting the opposite end of said beam member relative to said element.
- 60 8. In combination, an element having an opening, a closure plate for said opening disposed on one side of said element, a lever pivotally associated with said plate and with said element on the opposite side thereof, a beam member pivotally associated with said element adjacent to the pivotal connection between said lever and said element, a detachable connection between said beam member and the medial portion of said lever, and means for adjusting said beam member relative to said element to force said plate into closed position.
- 70 9. In combination, an element having an opening, a lever pivotally associated with said element and swingable through said opening, a closure plate for said opening pivotally associated with said lever, a beam member pivotally associated with said element and swingable away from said opening, means for detachably connecting said beam member to said lever, and means for adjusting said beam member relative to said element to force said plate into closed position with respect to said opening.
